FIDELITY CONTROL

Arthur V. Loughren, Tuckahoe, N. Y., assignor
to Hazeltine Corporation, a corporation of
Delaware

Application August 13, 1936, Serial No. 95,747

16 Claims. (Cl. 250—20)

This invention relates to modulated-carrier signal receivers, and more particularly to means for controlling the fidelity of signal reproduction of such receivers.

- 5 Various expedients have heretofore been proposed for controlling the fidelity of signal reproduction of modulated-carrier receivers. In the usual system for accomplishing this result, fidelity control is achieved indirectly by controlling 10 the selectivity of the receiver, it being well understood that the fidelity of signal reproduction is poor when the selector circuits of the receiver are sharply tuned to a desired carrier and optimum when the selector circuits are relatively 15 broadly tuned. The poor fidelity corresponding to sharp selectivity results from relative attenuation of the outer sideband frequencies with respect to the middle sideband frequencies. All the present known systems of fidelity control thus involve a compromise between fidelity and selectivity. The apparatus which has been proposed 20 for practicing the above-described methods of indirect fidelity control fall broadly into two classes, namely: apparatus susceptible to manual control; and apparatus designed automatically 25 to control the selectivity of the receiver in accordance with prevailing reception conditions. Manually operable selectivity control means, while generally satisfactory in operation, are difficult 30 for the unskilled operator to use successfully. Those arrangements which are automatic in operation eliminate this difficulty, but their construction involves relatively complicated and expensive circuit apparatus.
- 35 It is an object of the present invention, therefore, to provide a novel method and means for directly controlling the fidelity of reproduction of a signal modulated-carrier receiver without in any way modifying the action of the selective 40 circuits of the receiver.

It is a further object of the invention to provide, in a signal modulated-carrier receiver, a simple and inexpensive electric circuit arrangement for automatically and directly controlling 45 the fidelity of reproduction of the receiver inversely in accordance with the intensity of a desired received carrier.

More specifically, it is an object of the present invention directly to control the fidelity of a 50 modulated-carrier receiver by varying, in a relatively nonselective portion of the receiver, the modulation depth of the selected incoming modulated carrier.

The invention, as hereinafter described in detail, is illustrated in its application to a radio

broadcast receiver of the superheterodyne type. The objects of the invention, as set forth above, are realized by utilizing the modulation frequency component of the selected signal voltage to control the gain of at least one of the amplifier stages 5 in the radio-frequency channel of the receiver. The amplifier stages included in this portion of the receiver are usually relatively nonselective, the major portion of the selectivity being achieved in the intermediate-frequency channel of the receiver by sharply tuning the permanently tuned intermediate-frequency selector circuits. The attenuation of the outer sideband frequency components of the modulated carrier voltage resulting from the sharp tuning in this channel of the 10 receiver causes the ratio of the amplitude of these components to the amplitude of the sideband frequency components in the vicinity of the carrier frequency at the output of the selector circuits to be different from that existing in the 15 received modulation-frequency envelope. However, by controlling the gain of one or more of the high-frequency amplifier stages inversely in accordance with the amplitudes of the modulation-frequency envelope of the selected modulation 20 carrier, the sideband frequency components in the vicinity of the carrier frequency may be substantially attenuated in these stages without substantially affecting the amplification of the outer sideband frequency components. The result is a 25 flattening of the frequency-response characteristic of the receiver and a substantial improvement 30 in the fidelity of signal reproduction.

The desired change in the effectiveness of the fidelity control means is accomplished automatically and in such a manner that the fidelity of reproduction of the receiver varies directly in accordance with the intensity of a selected carrier. In one modification of the invention, the receiver is equipped with the regressive form of automatic 35 amplification control which, as is well known, is characterized with a rising A. V. C. characteristic such that increasing selected signal-carrier input is accompanied by increasing signal output. This increase in the signal detector output is utilized 40 to increase the effectiveness of the fidelity control means with increasing signal-carrier intensity, and vice versa. In another embodiment of the invention, progressive automatic amplification control is used in addition to the regressive 45 amplification control, and with this combination the signal detector output is maintained nearly constant for wide fluctuations in the selected-carrier intensity. Hence, supplemental means are required and are provided for varying the 50 55

effectiveness of the fidelity control means to obtain the desired variation in the fidelity of reproduction of the receiver with varying signal-carrier intensity.

5 The novel features which are believed to be characteristic of the invention are set forth with particularity in the appended claims. The invention itself, however, both as to its organization and method of operation, together with 10 further objects and advantages thereof, will best be understood by reference to the specification taken in connection with the accompanying drawing, in which the single figure illustrates the invention as applied to a radio broadcast receiver 15 of the superheterodyne type.

Referring now to the single figure of the drawing, there is shown, partly schematic, a complete superheterodyne receiver comprising a tunable radio-frequency selector 10 having its input circuit coupled to an antenna-ground circuit 11 and its output circuit coupled to the input circuit of a radio-frequency amplifier or repeater stage including a vacuum tube 12. The output electrodes of the tube 12 are, in turn, coupled to the 20 input circuit of a frequency changer 13. Coupled in cascade with the frequency changer 13 are an intermediate-frequency amplifier 14, a second intermediate-frequency amplifier 15, a signal detector 16, an audio-frequency amplifier 17, and 25 a translating device or sound reproducer 18. The signal detector 16 comprises a diode rectifier 19 which operates into a load circuit comprising a resistor 20 shunted by a carrier-frequency bypass condenser 21. The modulation-frequency 30 components of the voltage developed across the resistor 20 are impressed on the input circuit of the audio-frequency amplifier 17 through a coupling condenser 22.

In order to maintain the signal input to the 35 detector 16 within narrow limits for a wide range of signal intensities, there is provided automatic amplification control means comprising a diode rectifier 23 coupled to the output of the intermediate-frequency amplifier 14 and operating 40 into a load circuit including serially-connected resistors 24 and 25 shunted respectively by high-frequency bypass condensers 26 and 27. The junction point between the elements 24—27, inclusive, is grounded, as indicated. The rectified 45 voltage developed across the resistor 24 is passed through a filter comprising a series resistor 28 and a shunt condenser 29, and is applied negatively to an amplification control electrode of one or more of the tubes included in the intermediate-frequency amplifiers 14 and 15, the frequency changer 13, and the tube 12 through a connection 30'. It will be observed that the form of 50 automatic amplification control described above is regressive as to the radio-frequency amplifier including the tube 12, the intermediate-frequency amplifier 14, and the frequency changer 13, and is progressive as to the intermediate-frequency amplifier 15. This form of 55 amplification control provides a substantially flat A. V. C. characteristic such that the signal input to the detector 16 is nearly constant irrespective of wide fluctuations of the input signal-carrier intensity.

Fidelity control is obtained, as hereinafter explained, by means of a phase-shifting network 60 coupled between the load resistor 20 and a control electrode of the amplifier tube 12. In the arrangement shown, the control electrode of the tube 12, to which the phase-shifting network 65 is coupled, is the second grid removed from the

cathode of the tube, the first grid being the signal input grid. It will be understood that the same grid may, in certain applications, be used for both purposes. The application of the fidelity control to a separate grid is preferable, however, 5 since it ensures complete isolation of the fidelity control circuits from the radio-frequency channel of the receiver.

For the purpose of rendering the fidelity control means automatic in action so that the receiver is sharply selective when receiving a carrier of small intensity and is relatively broadly tuned when receiving a strong carrier, there is included in the coupling path between the phase-shifting network 30 and the resistor 20 a repeater comprising a vacuum tube 31. This tube has its input electrodes coupled to the resistor 20 through a condenser 32 and a control grid-bias voltage source 33, and its output electrodes coupled to the input terminals of the phase-shifting 20 network 30 through a condenser 34, anode potential being supplied to the tube through a resistor 35. The voltage of the source 33 is selected so that the tube 31 is initially biased considerably beyond cutoff. In order to vary the transmission efficiency, or gain, of the tube 31, directly in accordance with the intensity of a selected carrier when the carrier intensity exceeds a predetermined value, the unidirectional voltage developed across the resistor 25 is applied positively 30 to the control electrode of the tube through a filter resistor 36 to oppose the negative bias due to the source 33. It will be understood that the unidirectional voltage across the resistor 25 varies in magnitude directly with changes in the 35 selected signal-carrier strength and that when great enough to overcome the bias beyond cutoff occasioned by the source 33 renders the tube 31 operative to transmit to the phase-shifting network 30 the alternating modulation-frequency 40 voltage across the utilized portion of the resistor 20. If desired, the magnitude of the alternating voltage input to the tube 31 may be rendered adjustable to further vary the effectiveness of the fidelity control means by terminating the 45 connection from the control electrode of the tube 31 to the resistor 20 at an adjustable contact 37.

Neglecting for the present the action of the fidelity control means, the receiver described 50 above is of the conventional superheterodyne type, the operation of which is well understood in the art. In brief, the desired received signal-modulated carrier intercepted by the antenna-ground circuit 11 is selected in the selector system 10, amplified in the amplifier tube 12, converted into a signal-modulated carrier of fixed intermediate frequency in the frequency changer 13, further selected and amplified in the intermediate-frequency amplifiers 14 and 15, and supplied to the signal detector 16 for rectification. The modulation-frequency components of the 55 rectified voltage developed across the resistor 20 are transferred through the connection 22 to the audio-frequency amplifier 17 for amplification, after which they are supplied to the sound reproducer 18 for audio reproduction. The signal input to the detector is maintained within narrow limits for a wide range of received signal amplitudes through the action of the automatic 60 amplification control circuit comprising the rectifier 23, the filter network 28, 29, and the connection 30', in the manner described above.

It was pointed out above that, in the operation of a receiver of the type described, the selectivity 75

thereof is usually attained primarily in the intermediate-frequency channel by designing the intermediate-frequency selector circuits to be fairly sharply tuned to the intermediate-frequency carrier. This is necessary in order to prevent undue interference from strong undesired signals on carrier channels adjacent that of the desired channel. This means that, in the amplification of the carrier and sidebands in the intermediate-frequency channel, the outer sideband frequencies are discriminated against in favor of the middle range sideband frequencies, with the result that frequency distortion is present in the reproduced output and poor fidelity is obtained.

Such undesired discrimination is substantially obviated in accordance with the present invention through the action of the fidelity control means to control the amplification or gain of the radio-frequency amplifier stage including the tube 12 inversely in accordance with the modulation-frequency components of the received modulated carrier. To this end, a unidirectional voltage having an instantaneous amplitude proportional to the instantaneous amplitude of the modulation-frequency envelope of the selected carrier is developed across the load resistor 20 of the detector 16. This component of voltage is amplified in the repeater tube 31, is shifted in phase through the operation of the phase-shifting network indicated at 30, and is so applied negatively to the control electrode of the tube 12 that it is in exact phase opposition to the modulation-frequency component of the selected modulated carrier being amplified, and from which the signal-frequency control voltage is derived. It is pointed out that the phase-shifting network compensates only for the small phase shifts occasioned in the selector circuits included in the units of the receiver between the tube 12 and the detector 16, the desired 180 degree phase reversal of the modulation-frequency voltage being obtained in the repeated stage including the tube 31. The amplification in the tube 12 is, of course, decreased by an amount determined by the instantaneous amplitude of the feed-back control voltage and, since the instantaneous amplitude of this voltage is greatest at the sideband frequencies nearest the intermediate-carrier frequency, due to the sharp selectivity of the intermediate-frequency channel of the receiver, the amplification of the tube 12 is reduced to the greatest extent for voltage components of these frequencies. The result is, therefore, in effect, a demodulation of the selected carrier, or effective varying of the modulation depth of the carrier inversely in accordance with the separation of the sideband frequencies from the carrier frequency, whereby the width of the frequency transmission band of the receiver is effectively increased.

It will be understood that the demodulation of the carrier, in the manner described above, occurs only when the strength of the incoming selected carrier is above the predetermined value required to render the repeater tube 31 operative. With signal-carrier strengths above this predetermined value the transmission efficiency of the tube 31 is varied directly with the carrier intensity so that with a strong selected signal carrier considerable amplification of the demodulating voltage is obtained in the tube 31, with the result that the incoming carrier is demodulated to a large degree in the tube 12 and the effective

frequency transmission band through the receiver is relatively wide, and vice versa.

The necessity for employing the tube 31 and its associated amplification control circuit results from the use of the particular form of automatic amplification control means illustrated and described above. As was pointed out, this form of amplification control, employing both regressive and progressive control, is characterized by a flat A. V. C. characteristic which means that, if two signal carriers of different intensity but modulated to the same degree are received, the resulting modulation frequency voltage developed across the load resistor 20 will be of substantially the same magnitude in each instance. However, all commercial forms of automatic amplification control are not as effective to maintain the input to the signal detector 16 within such narrow limits as that described above. For example, in those receivers which depend entirely upon regressive action of the automatic control means for amplification control, the input to the signal detector increases with increasing signal strength with the result that the modulation-frequency voltage increases also. In those receivers which are constructed and arranged so that the A. V. C. characteristic rises in the above-described manner, it may be unnecessary to employ the tube 31 in the coupling path between the resistor 20 and the phase-shifting network 30, since the increasing magnitude of the modulation-frequency voltage, with increasing signal strength produced by the relatively imperfect amplification control, may be sufficient to provide the desired automatic effective expansion and contraction of the frequency transmission band of the receiver as the signal-carrier strength varies.

In the arrangements described above, the fidelity of reproduction of the receiver is controlled by varying the amplification or transmission efficiency of one or more of the modulated-carrier frequency amplifier, or repeater, stages, effectively to demodulate the selected carrier through the application, to a control electrode of the controlled tube or tubes, of a feed-back voltage of proper phase and polarity and proportional in amplitude to the amplitude of the modulation-frequency envelope of the selected carrier. The same result may be accomplished by properly designing the phase-shifting network 30 to discriminate against the middle range frequencies of the sidebands without attenuating the outer sideband frequencies, and applying the voltage output from the phase-shifting network to the control electrode of the tube 12 positively so that it is in phase with the modulation-frequency envelope of the selected modulated-carrier input to the tube 12.

With the latter arrangement, the feed-back voltage is effective to produce a relatively large increase in the gain or transmission efficiency of the tube 12 for modulation-frequency components of the signal corresponding to the outer sideband frequencies and only a small increase in the gain of the tube for components of the signal voltage having center sideband frequencies. The effect is, therefore, a broadening of the frequency transmission band of the receiver and, by varying the magnitude of the feed-back voltage directly in accordance with the intensity of a received carrier in the previously described manner, the fidelity of the receiver may be varied so that with strong signals the desired optimum fidelity is obtained and with weak signals the receiver is sharply selective.

Although the fidelity control means has been described as applying a control voltage to a single amplifier stage of the receiver, it will be understood that more than one stage may be subjected to identical control if the exigencies of a particular receiver so require. It is pointed out that similar results may be obtained by applying the control voltage to the amplifier tubes of one or more of the intermediate-frequency amplifier stages of the receiver.

While there has been described what is at present considered to be the preferred embodiment of the invention, it will be understood that various changes and modifications may be made therein without departing from the invention, and it is contemplated in the appended claims to cover all such changes and modifications as fall within the true spirit and scope of the invention.

20. What is claimed is:

1. In a modulated-carrier signal receiver, a modulated-carrier repeater stage including a vacuum tube having a control electrode, a frequency-selective network coupled to and following said stage, means for deriving from a received modulated carrier selected by said network a voltage having an instantaneous amplitude proportional to the instantaneous amplitude of the modulation-frequency envelope of said selected modulated carrier, and means for compensating at least in part for the frequency-response characteristic of said network comprising means for applying said voltage to said control electrode to vary the transmission efficiency of said repeater stage inversely in accordance with the amplitude of said modulation-frequency envelope of said carrier, thereby to control the fidelity of reproduction of said receiver.

2. In a modulated-carrier signal receiver, a modulated-carrier repeater stage including a vacuum tube having a control electrode, a frequency-selective network coupled to and following said stage, means for deriving from a received modulated carrier selected by said network a voltage having an instantaneous amplitude proportional to the instantaneous amplitude of the modulation-frequency envelope of said selected modulated carrier, and means including phase-shifting means for compensating at least in part for the frequency-response characteristic of said network comprising means for applying said voltage to said control electrode in the correct phase to vary the transmission efficiency of said repeater stage inversely in accordance with the instantaneous amplitude of the modulation-frequency envelope of said selected carrier, thereby to control the fidelity of reproduction of said receiver.

3. In a modulated-carrier signal receiver, a modulated-carrier repeater stage including a vacuum tube having a control electrode, a frequency-selective network coupled to and following said stage, a detector coupled to said network, means including said detector for deriving from a received modulated carrier selected by said network a voltage having an instantaneous amplitude variable with the instantaneous amplitude of the modulation-frequency envelope of said selected carrier, and means for compensating at least in part for the frequency-response characteristic of said network comprising means for applying said voltage to said control electrode to vary the gain of said amplifier stage inversely in accordance with the instantaneous amplitude of the modulation-frequency envelope

of said selected carrier, thereby to control the fidelity of reproduction of said receiver.

4. In a modulated-carrier signal receiver of the superheterodyne type, a radio-frequency repeater stage, a frequency-selective network coupled to and following said stage, a frequency converter, a detector, and means including said detector for compensating at least in part for the frequency-response characteristic of said network comprising means for varying the transmission efficiency of said repeater stage inversely in accordance with the instantaneous amplitude of the modulation-frequency envelope of a modulated carrier selected by said network, thereby to control the fidelity of reproduction of said receiver.

5. In a modulated-carrier signal receiver of the superheterodyne type, a radio-frequency repeater stage including a vacuum tube having a control electrode, a frequency-selective network coupled to and following said stage, a frequency converter, a detector including a load circuit, and means comprising means for applying to said control electrode for compensating at least in part for the frequency-response characteristic of said network comprising means for applying to said control electrode the modulation-frequency voltage developed across said load circuit to vary the transmission efficiency of said repeater stage inversely in accordance with the instantaneous amplitude of the modulation-frequency envelope of said carrier, thereby to control the fidelity of reproduction of said receiver.

6. In a wave signal receiver for receiving a selected signal comprising a carrier and at least one side-band, a modulated-carrier repeater stage, a frequency-selective network coupled to and following said stage, said network being most responsive at frequencies in the vicinity of the carrier frequency, and means for compensating at least in part for the frequency-response characteristic of said network comprising means for varying the transmission efficiency of said repeater stage inversely in accordance with the instantaneous amplitude of the sideband frequency envelope of said amplified signal, thereby to render said receiver substantially equally responsive to all frequencies included in said sideband.

7. In a wave signal receiver for receiving a selected signal comprising a carrier and at least one sideband, a modulated-carrier repeater stage for repeating said selected signal including a vacuum tube having a control electrode, a frequency-selective network coupled to and following said stage, said network being most responsive at frequencies in the vicinity of the carrier frequency, a signal detector, means including said detector for deriving from said signal a voltage having an instantaneous amplitude variable with the instantaneous amplitudes of the sideband frequency envelope of said signal, and means for compensating at least in part for the frequency-response characteristic of said network comprising means for applying said voltage to said control electrode to vary the transmission efficiency of said repeater means inversely in accordance with the instantaneous amplitude of the sideband frequency envelope of said signal, thereby to render said receiver substantially equally responsive to all frequencies included in said sideband.

8. In a wave signal receiver for receiving a selected signal comprising a carrier and at least one sideband, a modulated-carrier repeater stage

- for repeating said selected signal including a vacuum tube having a control electrode, a frequency-selective network coupled to and following said stage, said network being most responsive at frequencies in the vicinity of the carrier frequency, a signal detector, means including said detector for deriving from said signal a voltage having an instantaneous amplitude variable with the instantaneous amplitude of the sideband frequency envelope of said signal, and means including phase-shifting means for compensating at least in part for the frequency-response characteristic of said network comprising means for applying said voltage to said control electrode in the proper phase to vary the transmission efficiency of said repeater means inversely in accordance with the instantaneous amplitude of the sideband frequency envelope of said signal, thereby to render said receiver substantially equally responsive to all frequencies included in said sideband.
9. In a modulated-carrier signal receiver, a modulated-carrier repeater stage, a frequency-selective network coupled to and following said stage, means for carrying the transmission efficiency of said repeater stage inversely in accordance with the instantaneous amplitude of the modulation-frequency envelope of a modulated carrier selected by said network, thereby to control the fidelity of reproduction of said receiver, and means for varying the effectiveness of said last-named means to vary the fidelity of reproduction of said receiver directly in accordance with the intensity of said carrier.
- 35 10. In a modulated-carrier signal receiver, a modulated-carrier repeater stage including a vacuum tube having a control electrode, a frequency-selective network coupled to and following said stage, means for deriving from a received modulated carrier selected by said network a voltage having an instantaneous amplitude proportional to the instantaneous amplitude of the modulation-frequency envelope of said selected modulated carrier, means for varying the magnitude of said voltage directly in accordance with the intensity of said carrier, and means for applying said voltage to said control electrode to vary the transmission efficiency of said repeater stage inversely in accordance with the instantaneous amplitude of said voltage, thereby to control the fidelity of reproduction of said receiver.
11. In a modulated-carrier signal receiver, a modulated-carrier repeater stage including a vacuum tube having a control electrode, a frequency-selective network coupled to and following said stage, means for deriving from a received modulated carrier selected by said network a voltage having an instantaneous amplitude proportional to the instantaneous amplitude of the modulation-frequency envelope of said selected modulated carrier, automatic amplification control means for maintaining the magnitude of said derived voltage nearly constant for wide variations in the input intensity of said carrier, means for varying the magnitude of said voltage directly in accordance with the intensity of said carrier, and means for compensating at least in part for the frequency-response characteristic of said network comprising means for applying said voltage to said control electrode to vary the transmission efficiency of said repeater stage inversely in accordance with the instantaneous amplitude thereof, thereby to control the fidelity of reproduction of said receiver.
- 75 12. In a modulated-carrier signal receiver, a modulated-carrier repeater stage including a vacuum tube having a control electrode, a frequency-selective network coupled to and following said stage, means comprising a detector including a load circuit for developing across at least a portion of said circuit a voltage having an instantaneous amplitude proportional to the instantaneous amplitudes of the modulation-frequency envelope of a modulated carrier selected by said network, automatic amplification control means for maintaining the magnitude of said derived voltage nearly constant for wide fluctuations in the intensity of said carrier, means comprising a repeater for compensating at least in part for the frequency-response characteristic of said network comprising means for applying said voltage to said control electrode to vary the transmission efficiency of said first-named repeater stage inversely in accordance with the instantaneous amplitude of said voltage, thereby to control the fidelity of said receiver, and means comprising at least a portion of said amplification control means for varying the transmission efficiency of said second-named repeater directly in accordance with the intensity of said carrier, whereby the fidelity of reproduction of said receiver is varied directly in accordance with the intensity of said carrier.
13. In a modulated-carrier signal receiver, a modulated-carrier repeater stage including a vacuum tube having a control electrode, a frequency-selective network coupled to and following said stage, means for deriving from a received modulated carrier selected by said network a voltage having an instantaneous amplitude proportional to the instantaneous amplitude of the modulation-frequency envelope of a selected modulated carrier, automatic amplification control means for increasing the magnitude of said derived voltage with increasing intensity of said selected carrier, and means for compensating at least in part for the frequency-response characteristic of said network comprising means for applying said voltage to said control electrode to vary the transmission efficiency of said repeater stage inversely in accordance with the instantaneous amplitude of said voltage, thereby to vary the fidelity of reproduction of said receiver directly in accordance with the intensity of said carrier.
- 35 40 45 50 55 60 65 70 75 80 85 90 95 100
14. In a modulated-carrier signal receiver, a modulated-carrier repeater stage, a frequency-selective network coupled to and following said stage, and means for varying the transmission efficiency of said repeater stage for the modulated-carrier frequency signal by an amount proportional to the instantaneous amplitudes of at least a portion of the frequency components included in the modulation-frequency envelope of a modulated carrier selected by said network, thereby to control the fidelity of reproduction of said receiver.
15. In a modulated-carrier signal receiver, a modulated-carrier repeater stage including a vacuum tube having a control electrode, a frequency-selective network coupled to and following said stage, means for deriving from a modulated carrier selected by said network a voltage having an instantaneous amplitude variable with the amplitudes of at least a portion of the modulation-frequency components of a selected modulated carrier, and means for compensating at least in part for the frequency-response characteristic of said network comprising means for

applying said voltage to said control electrode to control the fidelity of said receiver.

16. In a modulated-carrier signal receiver, a modulated-carrier repeater stage including a vacuum tube having a control electrode, a frequency-selective network coupled to and following said stage, means for deriving from a modulated carrier selected by said network a voltage having an instantaneous amplitude variable with the amplitudes of at least a portion of the modulation-

frequency components of a selected modulated carrier, means for compensating at least in part for the frequency-response characteristic of said network comprising means for applying said voltage to said control electrode, and means for varying the magnitude of said voltage to vary the fidelity of reproduction of said receiver directly in accordance with the intensity of said carrier. 5
